BRUSH

Vincent B. Nyhan, Chicago, Ill.

Application February 18, 1959, Serial No. 54,663

Term of patent 14 years

(Cl. D9—2)

Fig. 1 is a top plan view of a brush showing my new design.

Fig. 2 is a front elevational view thereof; and

Fig. 3 is a side elevational view thereof.

The essential features of my design reside in the portions shown in full lines.

I claim:

The ornamental design for a brush, substantially as shown and described.
